UNITED STATES PATENT OFFICE.

NICOLA M. MASTROMONACO, OF BUFFALO, NEW YORK.

WINDOW SHADE.

Application filed October 2, 1926. Serial No. 139,107.

This invention relates generally to improvements in window shades but more particularly to means for holding the shade in any desired position.

One of its objects is to provide a holding means for window shades which is simple, compact and inexpensive in construction, which can be easily and conveniently operated, and which is not liable to get out of order.

Another object of the invention is the provision of improved means for guiding the shade in a straight path and for releasably locking the same in a fixed position.

A still further object is to provide means for rendering the shade-locking mechanism automatically operative when the shade is raised to a predetermined point.

In the accompanying drawings:—Figure 1 is a front view of a window frame showing my invention applied thereto. Figure 2 is an enlarged fragmentary face view of one end of the shade and its holding means. Figure 3 is an enlarged top plan view, partly in section, of one end of the shade-holding means. Figure 4 is an enlarged front view of the shade-bar or stick, partly in section, showing the holding means and their controlling mechanism in the normally locked position. Figure 5 is a fragmentary sectional view, similar to Figure 4, showing the controlling mechanism set in its unlocked position. Figure 6 is a horizontal section taken substantially in the plane of line 6—6, Fig. 4. Figure 7 is a transverse vertical section on line 7—7, Fig. 2.

Similar characters of reference indicate corresponding parts throughout the several views.

By way of example, the invention is shown in connection with a window frame 10 having a spring roller type of shade 11 journaled in suitable brackets 12 secured to the upper end of the frame. Attached to the opposite sides of the window frame and spaced forwardly therefrom are upright guide members or rails 13 which are preferably T-shaped in cross section, the cross bar 14 of each guide member being arranged at right angles to the frame and having a series of equi-distant horizontal notches 15 in its front edge. The flange 16 of each guide member faces inwardly and constitutes a trackway on which the shade is guided. Brackets 17

welded or otherwise fastened to these guide members serve to properly support them on the window-frame.

Contained in a transverse pocket 18 at the lower edge of the shade 11 is the shade-stick which carries the various parts of the holding mechanism. This stick, by preference, comprises a centrally disposed base plate 19 to the ends of which are secured oppositely-extending strips or core pieces 20, 20 over which corresponding metallic tubes 21, 21 of rectangular cross section are telescopically fitted. The outer ends of said tubes extend somewhat beyond the ends of their core pieces and mounted therein for adjustment lengthwise of the shade-stick are brackets 22 each having upper and lower grooved rollers 23, 23 arranged to engage the flange 16 of the corresponding T-shaped guide member 13 for guiding the shade in a true path during its raising and lowering movements. Projecting from opposite sides of these brackets are outwardly and inwardly bent lips or flanges 24, 24 which embrace the cross bar 14 of the guide members in the manner shown in Fig. 3 and together with the rollers 23 effectively prevent both longitudinal and transverse displacement of the shade-stick relative to the guide rails. The attaching inner end or shank of each bracket 22 is held in a set position by a U-bolt 25 passing through openings in its shank and through a pair of longitudinal slots 26 in the corresponding metallic tubes 21. By mounting the brackets in this manner, the shade-stick can be readily adjusted to suit window frames of varying widths within a certain range.

Located at the opposite ends of the shade-stick and carried by the brackets 22 for co-operation with the notches 15 of the guide rails are locking devices for positively holding the shade at any desired elevation. These locking devices consist of horizontally-swinging levers or latches 27 pivoted at 28 to the corresponding brackets, the outer arms of said latches being curved toward the guide rails and adapted to interlock with one or another of the notches therein. Springs 29 interposed between the inner arms of the latches and the opposing faces of the brackets act to normally urge the latches into locking engagement with the notches. As shown in Figs. 2 and 4, the front bracket-lips 24, which embrace one side of the guide rails 13, have

recesses 30 therein to permit the inner arms of the latches to freely pass therethrough into and out of their locked positions.

Means are provided for both manually and automatically controlling the simultaneous movement of the locking latches. The manual means, which also constitute a part of the automatic means, consists of an oscillating element preferably in the form of a small pulley 31 mounted on the base plate 19 of the shade-stick for movement about a horizontal axis. At its diametrically opposite sides this pulley has ears 32 to which are fastened the inner ends of flexible connections or wires 33, 34 which extend in opposite directions from said pulley and are suitably fastened at their outer ends to the inner arms of the respective latches, as shown in Fig. 4. These wires extend horizontally through corresponding grooves or passages 35 in the core pieces 20 and thence outwardly through registering slots or openings 36, 37 in the shanks of the brackets 22 and the end portions of the tubes 21, respectively, as seen in Fig. 4.

When the pulley is turned in a clockwise direction, the wires 33, 34 are simultaneously pulled inwardly to rock the latches 27 in a direction to release them from locking engagement with the rail-notches 15, and thus permit the shade to be raised or lowered. The pulley is actuated to release the latches through the medium of a finger ring 38 depending centrally from the lower edge of the shade and connected by a cord 39 with the pulley.

For the purpose of temporarily locking the pulley in the position shown in Fig. 5 and holding the latches in their released position shown by dotted lines in Fig. 3, a locking pawl 40 is provided which is pivoted at 41 to the base plate 19 and which is adapted to engage a notch 42 in the periphery of the pulley-flange 43 in such position, a spring 44 tending to urge the pawl into its notch. A finger ring 45 is arranged alongside the ring 38 and is connected by a cord 46 with the tail end of the pawl. When said ring 45 is pulled, it releases the pawl from locking engagement with the pulley, allowing the latch springs 29 to act and return the latches to their locked position. In so doing, the wires 33, 34 are likewise pulled in a direction to turn the pulley to its original position, shown in Fig. 4, wherein the pulley-notch is out of register with its locking pawl. It will be understood from the foregoing that when the finger ring 38 is pulled the shade is free to be raised or lowered, and when the ring 45 is pulled, the shade is locked against such movement.

If desired, means may be provided for automatically arresting the raising of the shade beyond a predetermined point. As shown in Fig. 4, a wire 47 connects the tail end of the pawl 40 with one arm of a rock lever 48 fulcrumed at 49 to the right hand bracket 22.

Pivoted to the other arm of said lever and guided for movement in a bearing 50 is a vertical plunger 51 having a spring applied thereto which tends constantly to raise the plunger and hold its rock lever in the normal position shown. Secured to the adjoining guide rail 13 or the adjacent side of the window frame and in the path of movement of the lever-actuating plunger is a trip arm 52, which acts to lower the plunger when the same strikes said arm upon raising the shade, thereby rocking the lever 48 in the proper direction to pull the wire 47 and release the pawl 40 from the pulley, with the result that the latches 27 are allowed to automatically return to their locked position in the same manner as if said pawl were actuated manually through its finger ring 45.

The oscillating movement of the pulley 31 is limited in either direction by a stop pin 53 projecting into a peripheral notch 54 in the pulley-flange 43. A cover plate 55 extends over the front side of the base plate 19 so as to completely encase the parts carried by it.

I claim as my invention:

1. A device of the character described, comprising a shade stick, a locking device applied to the end of the stick, manually-operated means connected with said locking device for moving it to its released position, retractable means for holding said manually-operated means in such released position, and means for effecting the automatic return of the locking device to its engaged position upon the retraction of said holding means.

2. A device of the character described, comprising a shade stick, a locking device applied to the end of the stick, an oscillating member mounted on the shade stick intermediate its ends, a connection between said member and said locking device, yieldable means for moving the oscillating member and the locking device to locked position, and releasable means for holding said parts in their unlocked position.

3. A device of the character described, comprising a shade stick, a locking device applied to the end of the stick, means operated manually in one direction and connected to said locking device for moving it to its released position, retractable means disposed alongside of and arranged to interlock with said manual means for holding the same in such released position, means for effecting the automatic return of the locking device to its engaged position and the manually-operated means thereof to a corresponding position upon the retraction of said holding means, and finger-engaging elements depending from the shade stick and connected with said manually-operated means and said retractable means, respectively, for actuating them.

4. A device of the character described, comprising a shade stick, a latch applied to the end of the stick, means for constantly urging

said latch to its locked position, an oscillating member arranged substantially centrally of the shade stick and having a locking notch therein, a connection joining said member 5 with said latch, a detent arranged to engage the locking notch of said oscillating member for holding it and the latch in unlocked position, and pull cords disposed in proximity to each other and attached to said oscillating 10 member and said detent for alternately actuating them to control the latch.

5. A device of the character described, comprising a shade stick, a latch applied to the end of the stick, means for constantly urging 15 said latch to its locked position, an oscillating member arranged substantially centrally of the shade stick, a connection joining said member with said latch, a detent arranged to engage the oscillating member for holding it and the 20 latch in unlocked position, means for actuating said oscillating member, and automatic means for actuating said detent including a lever fulcrumed at one end on the

shade stick, a connection between one arm of the lever and the detent, a part on the other 25 arm of said lever adapted to be tripped for moving the same in a direction to actuate the detent, and a trip element arranged in the path of said part to be tripped.

6. A device of the character described, comprising a shade stick, guide members for said stick applied to the ends thereof, latches mounted on said guide members to swing transversely thereof, springs for urging said latches to their locked position, an oscillating member journaled substantially centrally of the shade stick, flexible connections joining the opposite ends of said oscillating member with said latches, a detent arranged to engage the oscillating member for holding it and the latches in their unlocked positions, and pull cords attached to said oscillating member and said detent for alternately actuating them to control the latches.

NICOLA M. MASTROMONACO.
